UNITED STATES PATENT OFFICE.

FREDERICK REUTER, OF BROOKLYN, NEW YORK, ASSIGNOR TO JOHN C. GRAHAM, OF PHILADELPHIA, PENNSYLVANIA.

DESIGN FOR FRINGE.

SPECIFICATION forming part of Design No. 12,698, dated January 17, 1882.

Application filed August 27, 1881. Term of patent 14 years.

To all whom it may concern:

Be it known that I, FREDERICK REUTER, of Brooklyn, in the county of Kings and State of New York, have invented and produced a new 5 and original Design for Fringe, of which design the following is a specification.

The accompanying drawing is a side view of a section of fringe embodying and illustrating my design, which consists in fringe having a 10 flat tape or gimp heading, A, to which is attached at intervals a series of pendants, B, of substantially cylindrical contour, each composed of chenille threads twisted helically about the axis of the pendant and projecting loosely therefrom. The pendants B, which may be of any 15 desired color, either uniform in tint or shaded or striped, are ornamented by an end tuft, swell, or enlargement, b', formed of threads projecting to a greater extent than do those of the body

of the pendant, and by preference of color different therefrom, also by one or more similar swells, tufts, or enlargements, b², projecting from the body of the pendant between its free end and the heading A.

I claim—

A design for fringe, consisting of a flat tape or gimp heading and a series of pendants formed of loosely-projecting chenille threads, and ornamented by end swells, tufts, or enlargements formed of threads projecting beyond the contour of the body of the pendants, and by similar swells, tufts, or enlargements intermediate between the free ends of the pendants and the heading, substantially as set forth.

FREDERICK REUTER.
